UNITED STATES PATENT OFFICE

ROY H. LEDBETTER, OF FAIRFIELD, ALABAMA

WATER-COOLED TUYÈRE

Application filed October 14, 1927. Serial No. 226,136.

This invention relates to improvements in tuyères of the character used in producing the air blast for blast furnaces. Tuyères have been made heretofore with extension 5 walls for supporting a cementitious material intended to prolong the life of the tuyère. Experience has shown that quick cutting action of the blast combined with the abrasive 10 action of descending coke and fluxing by contact with the molten slag soon removes the material and exposes the metallic part of the tuyère to the destructive action of the slag, coke, ore, etc. in the furnace. My improved tuyère aims to overcome such disadvantages. In tuyères heretofore used, the aim has been to provide a material capable of withstanding extreme heat and the choice has usually been limited to a refractory material because of its capability of withstand- 15 ing high temperatures. My improved tuyère includes a precast hard burned, dense, fire-brick tile which is keyed or interlocked with the water wall of the tuyère. The material which I prefer to use is chosen not be- 20 cause of its refractory qualities but because of its ability to resist both the action of slag in the furnace and the abrasive action of coke and other materials charged to the fur- 25 nace.

30 An embodiment of the invention is illus- trated in the accompanying drawings in which—

Fig. 1 is a longitudinal section through the blast furnace tuyère;

35 Fig. 2 is a fragmentary section of the inner end of the tuyère, thus being a slight modification;

Fig. 3 is a sectional view illustrating a further modification.

40 Referring in detail to the drawings, the tuyère includes outer and inner substantially concentric walls 10 and 12 spaced apart suf- ficiently to form a chamber 14 for the circu- 45 lation of cooling water which is supplied by suitable pipes not shown which engage the threaded openings 16 and 18 formed in the outer wall 20 of the tuyère.

Near the front end of the tuyère shown in Fig. 1, I provide a wall 22 of substantially 50 V-shape in cross-section. This wall is

formed with outwardly extending projec- 55 tions 24 which interlock with suitable open- ings in a precast tile member 26. The front of the tuyère is curved over as shown so as to form a front or inner wall 28 which covers the front face of the tile 26. At a plurality of points, I provide cored holes 30, usually four in number.

The tile member 26 is precast and burned and is secured to or bonded in place in the tuyère during the casting thereof. In other words, the fire-brick ring 26 forms sort of a core about which the metal of the tuyère is poured. It is highly desirable to form the protective tile member 26 of a material capable of resisting the abrasive action of coke and other materials to be charged to the blast furnace. The material used should also be adapted to resist the action of furnace slag. Suitable materials for the formation of the tile 26 are aluminum oxide such as fused in the electric furnace and dense silicon carbide. These materials are more desirable than ordinary fire-brick as they offer greater resistance to abrasion and their glazed surfaces will retard slag penetration and, therefore, minimize the fluxing action of the molten contents of the furnace. Any of these materials can be precast into rings and formed with suitable recesses to cooperate with the diverging lugs 24 as shown in Fig. 1. Or the cross-sectional shape of the ring may be made like that shown at 26^a in Fig. 2 formed with recesses for coaction with the inclined lugs 24^a. Similarly, the protective tile may be of the cross-sectional shape indicated at 26^b in Fig. 3 so as to provide an annular dove-tailed groove 32 for coaction with the dove-tailed extension 34 cast in the wall 22^b 75 of the tuyère.

When the tuyère is put in service, the front metallic wall 28 will gradually be either eroded or burned away but the remaining part of the tuyère will be protected by the tile 95 ring 26 which as above mentioned is formed of material adapted to resist abrasion and fluxing action of the bath and slag. The tile as described is intimately bonded to or interlocked with the metal body of the tu- 100

yère so that it will not be readily dislodged even after the front wall 28 burns away.

Various modifications may be made without departing from the invention as defined in the appended claims.

5 What I claim is:—

1. A furnace tuyère comprising a water jacketed body portion having a precast tile incorporated and enclosed in an end portion thereof, said tile having a glazed outer skin adapted to retard slag penetration and to resist abrasion.

10 2. A blast furnace tuyère comprising a water jacketed body portion, the end of which encloses a tile having a glazed skin of greater density than the inner portion of the tile body.

15 3. A blast furnace tuyère comprising substantially or approximately cylindrical shells joined by transversely spaced walls, one of said walls having a precast tile member incorporated therein, said tile having a glazed outer surface adapted to retard slag penetration and resist the fluxing action of molten blast furnace burden materials.

20 25 In witness whereof, I have hereunto signed my name.

ROY H. LEDBETTER.
